KEYBOARD-OPERATED ELECTRONIC MUSICAL INSTRUMENT

Robert N. Poznanovich, 9526 S. Manistee,
Chicago, Ill. 60617

Filed Aug. 4, 1969, Ser. No. 18,536

Term of patent 14 years

Int. Cl. D17—03

U.S. Cl. D56—1

FIG. 1

FIG. 2

FIG. 3

FIG. 1 is a perspective view of a keyboard-operated electronic musical instrument, showing my new design;

FIG. 2 is a top plan view; and

FIG. 3 is a side elevational view, the opposite side being substantially a mirror image thereof.

I claim:

The ornamental design for a keyboard-operated electronic musical instrument, as shown and described.
